UNITED STATES PATENT OFFICE

MELLE E. LOWMAN, OF SYRACUSE, NEW YORK, ASSIGNOR TO LOWMAN FOLDING BOX CORPORATION, OF SYRACUSE, NEW YORK, A CORPORATION OF NEW YORK

FOLDING BOX

Application filed February 3, 1930. Serial No. 425,601.

The invention relates to certain improvements in paper boxes, preferably including a body portion and a telescoping cover, each constructed from single blanks of paper, 5 cardboard or the like, so scored and folded as to constitute a completely lined body section and a completely lined cover section, the various parts of each interlocked or secured to prevent accidental displacement, the outer 10 surfaces of the body and cover and the inner surfaces of the lining of each being provided with a coating or finish that will protect the contents of the box, more particularly metal ware, from corrosive or tarnishing effects due to some of the constituents of the 15 fibers from which the box material is made. The blanks are adapted to be shipped and stored either in flat or partly folded condition and to be made up as required into complete form.

The invention is illustrated in the accompanying drawings, in which:—

Fig. 1 is a perspective view of the complete box in partly opened relation.

Fig. 2 is a plan view of a typical blank used for constructing both the body and the cover.

Fig. 3 is a plan view showing the blank partly folded for convenience of shipment.

Fig. 4 is a fragmentary plan view of the blank partly folded.

Fig. 5 is a fragmentary perspective illustrating the interlocked end tabs or flaps before the end section and supplemental end section are folded thereover into enclosing relation.

Fig. 6 is a longitudinal section on line 6—6 of Fig. 7.

Fig. 7 is a plan view broken away in part.

Referring to Fig. 2 of the drawings, the blank forming the body section and the telescoping cover is of the general contour illustrated in said figure, it being understood that the cover forming blank is slightly larger than the blank from which the body portion of the box is formed. The description of the construction and mode of manipulating the body forming blank will, however, apply as well to the blank from which the cover is formed, so that it will be unnecessary to de-

scribe the two elements separately. As indicated in Fig. 2, 1 indicates that portion of the blank which constitutes the bottom of the box and 2 and 3 represent the respective side walls with score markings or creases between the same and the bottom section to facilitate folding. The supplemental side sections 4 and 5 are formed as extensions of the side members 2 and 3, respectively, with scores or creases between the members to permit the supplemental side members to be folded inward to constitute part of the lining of the box. Formed as an extension of the supplemental side member 4 is a bottom liner section 6, which is of substantially the same size and dimensions as the section 1, except for beveled sided notches 8, 8, which are excised from the ends of the section 6. As shown, the line of juncture between the section 6 and the supplemental side section 4 is defined by a crease or scoring. The supplemental side section 5 is provided with an extension 7, which is in the form of a relatively narrow tongue having beveled ends which register with the overlying beveled edges of the notches 8, when the parts are in folded relation, as hereinafter described.

Extending from the ends of the bottom section 1 are end sections 9 and 10, which are prolonged into somewhat narrower supplemental end sections 11 and 12, respectively, each of which terminates in narrow beveled ended tongues 13 and 13', respectively, which are adapted to interlock with the notches 8, when the parts are folded. As indicated, there are creases or scores between the ends of the bottom section 1 and the end sections 9 and 10, between said end sections and the supplemental end sections 11 and 12 and between said supplemental end sections and the tongues 13 and 13', respectively, to enable these sections to be folded along the creases or scorings in assembling the box member.

Extending from the ends of side sections 2 and 3 and the supplemental side sections 4 and 5 are flaps 19 and 20, respectively, each of the former being separated from the adjacent end section 9 or 10 by a slot or kerf 22, the line of juncture between the flaps 19 and 20 and the side and supplemental side sections 11 and 12 being defined by a crease or scoring.

being defined by creases or scores and the junction of the respective flaps 19 and 20 being also defined by creases to facilitate the folding of these members.

5. As indicated, the blank from which the telescoping cover is made is of the same shape as that forming the body of the box, but is of slightly larger dimensions and the blank for the cover is provided with generally elliptical openings 26, 26 symmetrically disposed about midway of the score markings between the side and supplemental side members, so that, when these members are in folded relation, the openings form finger notches to facilitate the removal of the cover.

- One face of the cardboard from which the blanks are cut is provided with a surface layer or glaze, which is impervious to the more or less corrosive elements of the paper stock. 20. from which the blank is made and thus finished surface constitutes the exterior surface of the box and the interior of the lining thereof, so that commodities packed in the box which would be attacked by the corrosive emanations 25. from the paper will be completely protected. This renders the box particularly well adapted for packing silver and plated ware, or other goods which would be subject to tarnishing if permitted to contact the uncoated portion 30. of the cardboard or the like.

- The blanks may be cut from stacks of cardboard, which may be relatively thin because of the double walled character of the box and its cover and, as stated, the blanks may be shipped and stored in flat stacked relation. In order to save space and also as an aid to the operator in setting up the box and its telescoping cover, the blanks are preliminarily folded in part, as indicated in Figs. 3 and 4; that is to say, the supplemental side section 5 is folded over on side section 3 with the tongue 7 overlying the bottom 1 and the supplemental side section 4 is folded over on the side section 2, so that the bottom covering section 6 completely overlies the bottom section 1 and the tongue 7. In order to complete the set up of the partly folded blank, the side and supplemental side sections 3 and 5 and 2 and 4, respectively, are bent along the scorings into position normal to the bottom 1. The respective pairs of tabs 19 and 20 are folded inwardly until they are normal to the bottom and to the side members of which they form extensions and are interlocked by telescoping the folds between the sections of the tabs 19 and 20 in the manner shown in Fig. 5. The end sections 9 and 10 are then bent upwardly until they are normal with the base, after which the supplemental end sections 11 and 12 are folded over the telescoping pairs of tabs 19 and 20 and the tongues 13, 13' are automatically bent along the creases separating the same from the supplemental end sections and snap into 60. the notches 8, 8 in the ends of the bottom cov-

ering section 6. It will be seen, therefore, that the telescoping interlock between each pair of folded tabs 19 and 20, the enveloping of these telescoping pairs of tabs by the end sections and supplemental end sections and the interlock between the tongues 13, 13' and the notches 8, 8 are effective in holding the box in its assembled form against deformation or displacement of any of the parts, so that the formed box is practically as strong 75 and rigid as any pasted box or one in which the several parts are secured together with mechanical means.

What I claim is:

1. A paper box consisting of a unitary blank including bottom, side and end sections, supplemental side and end sections to fold down and over the inner faces of the side and end sections, a bottom covering section formed as an extension of one supplemental side section and having beveled sides notches extending across its ends, and tongues on the ends of the supplemental end sections complementary to and adapted to fill and fit said notches and lie in the same plane with the 90 bottom covering section.

2. A paper box consisting of a unitary blank including bottom, side and end sections, supplemental side and end sections to fold down and over the inner faces of the side and end sections, flaps extending from the ends of the side and supplemental side sections separated from the end sections by kerfs and adapted to mutually interlock, a bottom covering section formed as an extension of one supplemental side section and having beveled sides notches extending across its ends, and tongues on the ends of the supplemental end sections to engage said notches complementary to and adapted to fill 100 and fit said notches and lie in the same plane with the bottom covering section.

In testimony whereof I affix my signature.
MELLE E. LOWMAN.
